Primary Examiner — Mary Ann Calabrese*Assistant Examiner* — Jennifer L Rempfer(74) *Attorney, Agent, or Firm* — Stiennon & Stiennon**CLAIM**

The ornamental design for a one piece garment, as shown and described.

DESCRIPTION

FIG. 1 is a front view of the one piece garment of my invention;

FIG. 2 is a rear view thereof;

FIG. 3 is a right side view thereof, with sleeves raised; and,

FIG. 4 is a left side view thereof, with sleeves raised. The broken lines comprised of short dashes in the drawings depict portions of the one piece garment that form no part of the claim.
